AMALGAMATOR

Charles F. Bird, American Falls, Idaho, assignor
of one-half to Basil Edwards, Salt Lake City,
Utah

Application July 18, 1933, Serial No. 681,015
Renewed September 19, 1935

2 Claims. (Cl. 209—197)

This invention relates to amalgamators of that class in which the ore in a finely divided condition passes through mercury, the mercury acting to retain the gold or other precious metal in the ore, the tailings being discharged from the machine, freed from the precious metal.

The general object of this invention is to provide a very simple and thoroughly effective amalgamator of this character in which the ore is not subjected to the action of gravity but in which the ore is positively carried over the mercury and therethrough by means of a screw, the ore being agitated constantly by means of paddles mounted on the screw shaft and a further object in this connection is to provide a construction of this character wherein the shaft, screw and paddles are fixed from vertical movement and the trough is adjustable at either end so that a slight inclination may be given to the trough in either direction and so that the trough may be bodily raised or lowered with relation to the paddles and screw to thus prevent the paddles and screw from coming in contact with the mercury, and a further object is to provide a trough whose bottom is divided into compartments by transverse partitions and provide beaters or strikers adapted to impact against the bottom of the trough to dislodge material therein and prevent the material from adhering to the side wall of the trough.

Other objects will appear in the course of the following description.

My invention is illustrated in the accompanying drawings, wherein:—

Figure 1 is a longitudinal sectional view through an amalgamator constructed in accordance with my invention;

Figure 2 is an end view thereof;

Figure 3 is a section on the line 3—3 of Figure 1 looking in the direction of the arrows.

Referring to these drawings and particularly to Figure 3, it will be seen that the supporting frame for the amalgamator consists of the legs 10 and the cross braces 11 supported on said legs, the legs being connected to each other by longitudinal members 12 and by braces 13. Disposed within the frame is the trough 14 approximately U-shaped in cross section made of any suitable material, this trough having at its ends the cross pieces 15. These are engaged by the adjusting screws 16 extending down through the cross pieces 11 and have screw-threaded engagement therewith and have swiveled engagement with the cross pieces 18. Thus the trough may be raised or lowered, either bodily or one end of the trough may

be raised higher or lower than the other end of the trough.

Mounted upon transversely extending bearing brackets 17 are the bearings 18 for a longitudinally extending shaft 19. Mounted upon this shaft is the screw conveyor 20, certain of the blades of which are cut away at 21. Disposed between the threads of this conveyor are the paddles 22, each paddle having a shank 23 extending through the shaft and held to the shaft by the nuts 24.

It will be seen that the trough may be adjusted vertically with reference to the shaft so that the paddles and the blades of the conveyor may dip into the trough to a greater or less extent.

The bottom of the trough is divided into a number of separate compartments by transverse partitions 24 and 25. As illustrated, there are four of these compartments, the first three of which are to be partially filled with mercury designated 26. The other compartment is unfilled. It has a small discharge aperture from it.

It will be noted from Figure 1 that neither the paddles nor the blades of the conveyor 20 touch the mercury. For the purpose of dislodging any particles of ore which might become adhered, as it were, to the bottom of the trough, I provide a series of strikers. Each striker is designated 27 and as illustrated in Figure 3, each striker is pivotally mounted upon a shaft 28. Each striker has an upwardly extending head 29 which may be provided with a rubber or leather buffer 30, if desired, and each striker has a tail 31 adapted to be actuated by a cam 32 mounted upon a shaft 33. There will be as many of these cams as there are strikers and preferably there will be one striker disposed beneath each compartment. The strikers are urged toward the bottom of the trough by means of springs 34 and drawn away from the bottom of the trough by the cams 32 rotating in the direction of the arrow in Figure 3. As soon as the cam has passed the tail 31 of the striker, the spring will act to throw the head violently against the bottom of the trough and jar the trough.

The shaft 33 may be driven in any suitable manner but I have shown the shaft as being driven by a sprocket chain 35 passing over a sprocket wheel 36 on the shaft 28 and over a sprocket wheel 37 on the screw shaft 19, this screw shaft being in turn driven by means of a band wheel 38 or by any other suitable means. A trough 39 receives the discharge from the amalgamator trough.

In the operation of this amalgamator, ore in a finely comminuted condition and washed and screened is fed into the trough in any suitable manner preferably at the head thereof and is carried longitudinally along the trough by the conveyor. The gold will naturally sink to the bottom, the gangue being lightest and the gold will be caught and retained by the mercury disposed between the partitions. If any gold should drop to the bottom of the last compartment of the series where no mercury is retained, the gold will pass out eventually through the opening 40 into the discharge trough 39. I have found that in actual practice, this amalgamator secures a relatively high yield of gold and a relatively great separation of the gold from the gangue and I believe this is due particularly to the fact that the ore is caused to travel through the drum at a speed necessary with any particular ore by means of the conveyor 20. The agitation which the ore receives causes all of the gold to sink and come in contact with the mercury and the strikers act to jar the fine gold into the quicksilver. Preferably the trough and also the conveyor shaft will be very slightly elevated at the discharge end, thus holding the values back and giving the gold plenty of time to amalgamate. It will be seen also that the trough itself may be adjusted independently at either end and independently of the conveyor and paddles. It is to be understood that preferably the frame of this machine will be so constructed as to be slightly higher at the discharge end of the conveyor than at the inlet end. The conveyor 19 will also be disposed at the same level as the frame, slightly higher at the discharge end than at the inlet end. The trough is suspended more or less at the same pitch or level as the conveyor and under these circumstances when the mercury is put in, it will be slightly deeper at the lower end of each compartment. The adjustments at both ends of the trough, namely the screw 16, are necessary in order to lift or lower the trough according to the amount of amalgam that has accumulated. If desired, there can be ten pounds of mercury or fifty pounds of mercury used and the machine can be adjusted to suit any amount, the trough being so disposed as to bring the worm and paddles as close to the amalgam as possible 50 at all times without stirring the amalgam up. If the ore is sufficiently stirred and agitated, the

gold and other metals will naturally settle to the bottom and amalgamate with the quicksilver before they have any chance to be carried away. With my construction, the ore is being continually agitated and at the same time being fed forward and thus the gold and other heavy metals have ample opportunity to descend into the mercury. The purpose of the strikers 21 is to jar the fine gold on to the quicksilver, leaving a clean surface at all times and these strikers also keep the gold from sticking to the sides of the trough. Paddles 22, 23 are adjustable as shown in Figure 2 so that the paddles may be lengthened or shortened to bring them all at the same distance from the mercury. Each compartment, of course, has a plug so as to remove amalgam when cleaning up and in each compartment, of course, the mercury is deeper at the discharge end of the compartment than it is at the inlet end of the compartment. Obviously many minor changes might be made without departing from the spirit of the invention as defined in the appended claims.

I claim:

1. An amalgamator including a supporting frame, a trough having its bottom formed to provide a series of relatively shallow transversely extending mercury containing compartments, means for supporting the trough on the frame and vertically adjusting the trough independently at either end relative to the supporting frame, a shaft mounted on the frame, extending longitudinally of the trough and carrying a screw conveyor, paddles mounted upon said shaft, strikers disposed below the trough and adapted to impact against it, springs projecting the strikers against the trough and means for retracting the strikers.

2. An amalgamator including a trough having its bottom formed to provide a series of relatively shallow transversely extending mercury containing compartments, means for vertically adjusting the trough at either end, a shaft extending longitudinally of the trough and carrying a screw conveyor, paddles mounted upon said shaft, strikers disposed below the trough and adapted to impact against it, means for retracting and projecting the strikers, including a cam shaft, cams thereon, and means for rotating the conveyor shaft and cam shaft.

CHARLES F. BIRD.
